GLOW SWITCH

Francis D. Graham, West Orange, N. J.

Application March 29, 1949, Serial No. 84,147

7 Claims. (Cl. 200—113.5)

1

This invention relates to a glow switch, and has for an object to provide a glow switch that is non-chattering. A glow starter switch is used for electric discharge lamps and comprises a discharge tube for connection between the lamp electrodes and in which a glow discharge heats a bimetallic which is thus caused to bend and close contacts. The closure of the contacts causes the glow discharge to cease so that the contacts open, thereby breaking a circuit containing reactance. The resulting voltage surge causes a discharge in the lamp to start.

When the glow discharge ceases, the bimetallic strip cools relatively slowly, the contacts open relatively slowly and there is a tendency for the contacts to arc, thus reheating the bimetallic strip in the circuit, reclosing the circuit, then reopening again in a continuous chatter resulting from the arcing and reheating of the metallic strip in the circuit.

It is an object of this invention to remove the bimetallic strip from the circuit when the circuit is completed so that when the inevitable arcing occurs, it does not reheat the bimetallic strip, and there is no chattering with resulting unsatisfactory operation of the electric discharge lamp it is controlling.

A further object of this invention is to provide a non-chattering glow starter switch wherein a bimetallic strip causes the electrodes to close a circuit, without it being itself part of the final circuit, and wherein arcing as the circuit reopens does not reheat the bimetallic strip.

A further object of this invention is to provide a glow starter switch wherein there is a thermal and electric conductor connected to the electrode or contact carried by the bimetallic strip, which conductor both carries the electric current and conducts the heat caused by arcing away from the electrode without going directly through the bimetallic strip, thus permitting the switch to positively reopen as desired without any chattering.

A still further object of this invention is to provide a non-chattering glow switch that is positive in action, yet is simple and relatively inexpensive to construct, and does not involve any complicated elements that both add to the cost of construction and possibility of improper operation.

The foregoing and other objects of the invention will become more apparent as the description proceeds with the aid of the accompanying drawing, in which:

Fig. 1 is a sectional view through a switch glass

2

envelope showing the details of the glow switch, and

Fig. 2 is a similar view of another form.

There is shown at 10 the usual sealed glass envelope having the usual internal boss 11 through which extends the conductors 12 and 13 connected to the electrode posts 14 and 15. Mounted on the electrode post 14 as by welding is the customary bimetallic strip 16, which in operation in the conventional glow switch, would complete its circuit with the electrode post 15. In this invention, however, a link 17 is secured on the end of the bimetallic strip 16 and in turn has mounted on its other end an insulation bead 18 of glass or other insulation material.

Also secured on the bead 18 but spaced from the link 17 is a stub electrode or contact 20 which projects slightly toward the electrode post 15. Attached to this stub electrode or contact 20 is 20 a conductor 21, which, in the form in Fig. 1, has its other end attached to the electrode post 14 at 22 within the glass envelope but at a substantial distance from the bimetallic strip 16.

In the form in Fig. 2, the conductor 21' is not 25 connected directly to the bimetallic electrode post, but instead, is connected at 23 to a third post 24 extending through the glass envelope boss 11' and connected at 25 to the conductor 12', the other parts in Fig. 2 being identical with those 30 in Fig. 1.

In operation, instead of the end of the bimetallic strip completing the circuit with the electrode post 15, the bimetallic strip is not at all in the electric circuit when the circuit is completed, 35 but instead, the stub electrode or contact 20, carried thereby via the bead 18, closes the circuit when the glow heats up the bimetallic strip 16. The electric circuit is completed through the electrode post 15 to the stub electrode or contact 20, 40 the conductor 21, through connection 22 to the electrode post 14 and through the conductor.

In Fig. 2, the circuit is completed through conductor 21' to point 23 and third post 24 and through connection 25 to the conductor 12'.

In operation, when the voltage is applied, a glow takes place at the electrodes and the bimetallic strip 16 within the envelope 10, heating the electrodes and the bimetallic strip. This heating of the bimetallic strip 16 causes the 50 of the bimetallic strip 16 to open, moving its bead 18 and contact end until the stub electrode or contact 20 contacts the electrode post 15.

As the circuit is closed by the stub electrode post or contact 20 contacting electrode post 15, the glow in the bimetallic strip 16 is discontinued,

thus ceasing to heat the bimetallic strip 16, and allowing it to contract again, thus breaking the circuit between electrode post 15 and the stub electrode or contact 20. As the stub electrode or contact 20 moves away from the electrode post 15, any arcing that may occur will occur between the electrode post 15 and the stub electrode or contact 20. The heat from such arcing will not heat the bimetallic strip 16 because of the presence of the non-conducting glass bead 18, and instead, the heat will flow along the conductors 21 to the electrode post 14, in Fig. 1, at a point 22 substantially removed from the bimetallic strip 16, and in Fig. 2, to the third electrode post 24 and thus at 25 to the conductor 12', even more removed from the vicinity of the bimetallic strip 16. Thus, there is no possibility of reheating of the bimetallic strip 16 by any arcing, and hence it will continue to cool and move the stub electrode or contact 20 away from the electrode post 15, and no chattering can take place.

Since certain further changes can be made in the foregoing constructions, and different embodiments of the invention may be made without departing from the scope thereof, it is intended that all matter shown in the accompanying drawing or described hereinbefore shall be interpreted as illustrative, and not in a limiting sense.

What is claimed is:

1. A non-chattering glow starter switch comprising a sealed impervious envelope and a pair of electrode posts extending into said envelope, a bimetallic strip mounted at one end on one of said posts and arranged to extend toward the other of the posts, an insulating member linked to the free end of said bimetallic strip, a stub electrode mounted on said insulating member and arranged to contact the other post as the bimetallic strip is extended, and a conductor member thermally and electrically connecting said stub electrode to the bimetallic strip mounted electrode post at a point substantially remote from the bimetallic strip mounting thereon.

2. A non-chattering glow starter switch comprising a sealed impervious envelope and a pair of electrode posts extending into said envelope, a bimetallic strip mounted at one end on one of said posts and arranged to extend toward the other of the posts, an insulating member linked to the free end of said bimetallic strip, a stub electrode mounted on said insulating member and arranged to contact the other post as the bimetallic strip is extended, and a conductor member thermally and electrically connecting said stub electrode to the bimetallic strip mounted electrode post at a point substantially remote from the bimetallic strip mounting thereon, said thermal and electrical conducting member including a third post extending through the envelope and connecting to said bimetallic post outside of said envelope.

3. A non-chattering glow starter switch comprising a sealed impervious envelope and a pair of electrode posts extending into said envelope, a U-shaped bimetallic strip mounted at one end on one of said posts and arranged to extend toward

the other of the posts, an insulating bead linked to the free end of said bimetallic strip, a stub electrode mounted on said insulating bead and arranged to contact the other post as the bimetallic strip is extended, and a conductor member thermally and electrically connecting said stub electrode to the bimetallic-strip mounted electrode post at a point substantially remote from the bimetallic strip mounting thereon.

4. In a glow starter switch having a sealed glass envelope containing a pair of electrode posts and a U-shaped bimetallic strip mounted on one post and arranged to extend its free end toward the other post; means for providing a non-chattering contact between said electrode posts comprising a contact member carried by but insulated from the free end of the bimetallic strip and a thermal and electrical conductor connecting said contact member to the electrode post, on which the bimetallic strip is mounted, at a point remote from the strip mounting.

5. In a glow starter switch having a sealed glass envelope containing a pair of electrode posts and a U-shaped bimetallic strip mounted on one post and arranged to extend its free end toward the other post; means for providing a non-chattering contact between said electrode posts comprising a contact member carried by but insulated from the free end of the bimetallic strip and a thermal and electrical conductor connecting said contact member to the electrode post, on which the bimetallic strip is mounted, at a point remote from the strip mounting, said remote point being outside of the envelope.

6. In a glow starter switch having a sealed glass envelope containing a pair of electrode posts and a U-shaped bimetallic strip mounted on one post and arranged to extend its free end toward the other post; means for providing a non-chattering contact between said electrode posts comprising a contact member, an insulating bead carried by the free end of the bimetallic strip, said contact member being mounted on said insulating bead, and a thermal and electrical conductor connecting said contact member to the electrode post, on which the bimetallic strip is mounted, at a point remote from the strip mounting.

7. In a glow starter switch having a sealed glass envelope containing a pair of electrode posts and a U-shaped bimetallic strip mounted on one post and arranged to extend its free end toward the other post; means for providing a non-chattering contact between said electrode posts comprising a contact member, an insulating bead carried by the free end of the bimetallic strip, said contact member being mounted on said insulating bead, and a thermal and electrical conductor connecting said contact member to the electrode post, on which the bimetallic strip is mounted, at a point remote from the strip mounting, said remote point being outside of the envelope.
